(57) **CLAIM**

The ornamental design for a hand held electric grinder, as shown and described.

DESCRIPTION

FIG. 1 is a side perspective view of a hand held electric grinder showing my new design;
 FIG. 2 is a front view thereof;
 FIG. 3 is a rear view thereof;
 FIG. 4 is a side view of the opposite side of FIG. 1 thereof;
 FIG. 5 is a top view thereof; and,
 FIG. 6 is a bottom view thereof.

1 Claim, 6 Drawing Sheets*FIG. 1*

FIG. 2

Continuation application and continuation-in-part application, and a continuation of U.S. patent application number 09/510,333, filed on March 1, 2000, and entitled "Faucet Assembly".

FIG. 3

FIG. 4

FIG. 5

FIG. 6
